UNITED STATES PATENT OFFICE.

NICHOLAS CLUTE, OF SCHENECTADY, NEW YORK.

FEED-WATER REGULATOR.

SPECIFICATION forming part of Letters Patent No. 247,889, dated October 4, 1881.

Application filed May 31, 1881. (No model.)

To all whom it may concern:

Be it known that I, NICHOLAS CLUTE, a citizen of the United States, residing at Schenectady, in the county of Schenectady and State of New York, have invented certain new and useful Improvements in Automatic Feed-Water Regulators for Steam-Boilers; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to an automatic feed-water regulator for steam-boilers, the object being to provide an apparatus by which a constant supply of warm or hot water is fed to the boiler, so as to maintain a positive water-line therein, and thus obviate the liability to explosion that results from the ordinary intermittent feed.

The invention consists, first, in the combination, with a steam-boiler and supply-pump, of a cut-off check-valve and receiver, whereby water is constantly supplied to the boiler and the overflow returned to the supply-pump through the intermediate connections; second, in a cut-off check-valve consisting of a case containing a valve-seat and inclosing a valve attached to a stem projecting through a packing-box at the upper part of the case, and carrying a cross-bar for engagement with a trip attached to a yoke or a pump plunger, said valve being held to its seat by pressure of water and steam from a boiler which connects with the valve-case above the valve, and by the tension of a spiral spring bearing upon the top of the valve-stem; third, in the combination, with a steam-boiler, a receiver for both hot and cold water, and a cut-off check-valve, of one or more pumps, as hereinafter more fully set forth.

In the annexed drawings, which fully illustrate my invention, Figure 1 is a front view, partly in section. Fig. 2 is a top-plan view, partly in section. Fig. 3 is an end view with boiler removed. Fig. 4 is a sectional elevation of an ordinary check-valve. Fig. 5 is a sectional elevation of my improved cut-off check-valve, and Fig. 6 represents a modified form of my feed-water apparatus.

Similar letters of reference indicate corresponding parts in the several views.

The letter A designates a steam-boiler, which is provided with a supply-pipe, a, that connects with the supply-pump B through the bend or connection a', which contains an ordinary check-valve. This pump B is supplied with water from the receiver C through a pipe, a², a connection, a', being interposed, which also contains a check-valve. The receiver C is connected with a pipe, D, having a branch, d, for the reception of cold water from any suitable supply, and a branch, d', which connects with the hot-water pump E. This pump is supplied with hot water from the boiler by the pipes e e'. Between the pipes e e' is a cut-off check-valve, F, which regulates the quantity of overflow-water and steam supplied to the pump E. It will thus be seen that the overflow hot water is mixed with cold water in the pipe D, and thence passed to the receiver C. The receiver C has an overflow-nozzle, c, at the side, and an air-vent, c', at the top.

The cut-off check-valve, arranged to communicate with the pipes e e', consists of a casing, F, which is screw-threaded at its lower end to receive the pipe e, and has a screw-threaded opening in its side for the reception of the overflow-pipe e'. This case is made in sections, and contains a valve-seat, f, for a cup-valve, F', having a notched rim, f'. The cup F' is attached to a valve-stem, G, which passes through a packing-box, G', at the top of the case, and carries on the outer side a cross-bar, g, which engages with the trips h h, that are attached to a yoke, H, secured to the beam I. These trips are each provided at their ends with a shoulder, through which passes a set-screw, h', that may be adjusted to vary the lift of the valve. The sliding cross-bar g is perforated for the passage of the guide-studs i i, which support at their upper ends an adjustable cross-bar, k, which is held in place by the adjusting-nuts l l on the upper screw-threaded ends of the studs. The adjustable cross-bar k is provided with a downward-projecting pin, m, which serves as a guide for a spiral spring, m', which connects the cross-bar k with the upper end of the valve-stem G. By this means it will be seen that after the valve-cup F has been raised by the trips h h acting upon the cross-bar g to permit the passage of

hot water from the boiler to the hot-water pump and receiver, it is again seated to cut off this supply by means of the pressure of the inflowing water and steam from the pipe e' , which acts to partially close the valve when the trips descend from under the cross-bar, and this result is rendered certain and positive by the pressure of the spring m' upon the top of the valve-stem.

10. The supply-pump B and hot-water pump E are respectively connected by their plungers b e^2 with the yokes H H' , attached to the beam I, which is supported in a suitable frame, K, and connected by a rod, k' , with a suitable engine.

15. It will be observed that by this apparatus I am enabled to secure a constant automatic feed to the steam-boiler, so as to maintain therein a uniform water-line, thus obviating the danger of explosion.

20. It will also be seen that by passing the overflow-water and steam from the boiler to a receiver, which is also supplied with cold water, I am enabled to heat the latter without the necessity of employing the ordinary heater.

25. By arranging the cut-off check-valve F to be operated by the supply-pump B instead of by the hot-water pump E, I find that I can dispense with the latter pump and with the beam I. In this case the cut-off check-valve may be attached to a standard, K' , near the supply-pump and operated by the trips h h , attached to a yoke, H' , connected with the plunger b , as shown in Fig. 6. The hot-water pump E being dispensed with, the pipe e is connected directly with the receiver C, and the cold-water pipe d is attached thereto. This makes a more simple and economical arrangement of parts, and one that operates equally well as the construction

30. heretofore described, the pressure of overflow-water from the boiler being sufficient to supply the receiver with hot water without the necessity of employing a hot-water pump.

35. In order to assist the action of the supply-

pump, an ordinary check-valve, M, (shown in Fig. 4,) is placed in the bend a' , on each side of the pump, the operation of which will be readily understood.

What I claim is—

40. 1. In an automatic feed-water regulator for steam-boilers, a receiver for hot and cold water, having an overflow-nozzle, an air-vent, a supply pipe or pipes for hot and cold water, and an outlet to a supply-pump for the boiler, substantially as described.

45. 2. In an automatic feed-water regulator for steam-boilers, a cut-off check-valve having an entrance for water and steam above the valve, and a valve-stem extending up through a packing-box and actuated to positively seat the valve by a spiral spring, substantially as shown and described.

50. 3. In an automatic feed-water regulator for steam-boilers, the combination of the cut-off check-valve F with the means for operating the same, consisting of the trips h h , attached to a pump or its connections, substantially as shown and described.

55. 4. In an automatic feed-water regulator for steam-boilers, the combination, with the boiler A and supply-pump B, connected by pipe a , of the receiver C, having one or more inlets for hot and cold water, an outlet to the pump, an overflow-nozzle, and an air-vent, and the cut-off check-valve F, placed between said boiler and receiver, and communicating with each through the pipes e e' , respectively, whereby the overflow hot water from the boiler is conveyed to the receiver to heat the incoming cold water, and the whole automatically fed to the boiler, substantially as shown and described.

60. In testimony whereof I affix my signature in presence of two witnesses.

NICHOLAS CLUTE.
